UNITED STATES PATENT OFFICE.

CHARLES A. GERSTBACHER, OF WASHINGTON, DISTRICT OF COLUMBIA.

HAT AND CLOAK RACK.

SPECIFICATION forming part of Letters Patent No. 739,852, dated September 29, 1903.

Application filed February 21, 1903. Serial No. 144,407. (No model.)

To all whom it may concern:

Be it known that I, CHARLES A. GERSTBACHER, a citizen of the United States of America, residing at Washington, in the District of Columbia, have invented certain new and useful Improvements in Hat and Cloak Racks, of which the following is a specification.

My invention relates to certain improvements in hat and cloak racks, and has for its objects to provide a substantial, ornamental, and convenient rack for the purpose herein-after set forth.

It is specially adapted for use in hotels, amusement-halls, at receptions, and other entertainments where guests or patrons are required to deposit their hats, cloaks, &c., before entering, and it provides suitable means whereby such articles of apparel can be so placed thereon without folding or packing, as is now required in such places, owing to the method of using boxes or shelves for the purpose.

The manner in which my rack is constructed provides a greater hook capacity than ordinarily attained, owing to the free use of both the outside and inside of the hook-carrying frame and by providing extended ends to said frame, all being supported by one set of standards, occupying a limited amount of floor-space; furthermore, by constructing it so that it can be folded and stored away provides means whereby owners can use one or more, as necessity may demand. This is particularly advantageous in hotels at the entrances to their dining-rooms. Where ordinarily one rack would be sufficient, there are times when more would be necessary. It is usual to have an attendant in charge of these racks, who gives numbered checks (corresponding to numbers on or near the hooks) for identification, and with a rack of this description the attendant (usually a boy) can wait upon a greater number of guests in a shorter length of time than is usual, avoiding the necessity of delay to the guests, especially during rush hours. It pleases the patrons of these places to see their wearing-apparel well taken care of, and it lessens the expense to the proprietors of such places in that the labor is less and damage to apparel is entirely obviated, for which the proprietor is responsible. These

objects I attain by the means illustrated in the accompanying drawings, in which—

Figure 1 is a perspective of my improved rack; Fig. 2, a view showing it in a folded position, and Fig. 3 a detail view.

In the drawings, A A' indicate the halves of a rectangular frame carrying hat and coat hooks, having longitudinal side bars B B' and 60 transverse ends C C', the side bars being connected by hinges a. Rigidly secured thereto or formed integral therewith are the extended ends D D' for the purpose hereinafter described. The transverse ends are hinged 65 at their centers at E E' and rest upon standards F F', provided at their lower ends with transverse extended feet G G'. Connected to the lower ends of the standards by means of hinges H H' are longitudinal bars I I', they 70 being connected together by a hinge J on the under face thereof.

To retain the hook-carrying frame in a horizontal position, rods K, secured to the standards at L, are used, said rods having hooked 75 ends to engage eyes M, secured to the under side of the extended ends, or sliding plates N, located adjacent to the line of separation of the parts A A', can be used, adapted to engage a keeper secured to the opposite part. 80 One or both of these securing devices can be used for the purpose. The extended ends increase the hook capacity of the frame convenient to the attendant in charge, without additional amount of floor-space and serve 85 to make the rack more ornamental. Moreover, being extended in the opposite direction from the hinges than the rectangular part of the frame it serves to act as a counterbalance for any weight suspended from 90 the hooks of the central part of the frame, and if made of sufficient length and weight, or weighted, will counteract the weight on the rectangular frames without the use of securing devices. 95

In operating the attendant in charge will first cover the hooks on the extended ends to resist any pressure brought to bear upon the central part, and after utilizing the hooks on the outside of the rack and more hooks are 100 needed he abandons the use of one hook on the outside to form a passage to the inside of the frame to use the hooks therein. I preferably use timber rectangular in cross-sec-

tion to construct the racks and of a size four inches by four inches. This adds weight and stability to the structure, also allowing the use of heavy fastening devices for the 5 hooks and separating sufficiently the rows of hooks on the outside and inside, so that garments suspended from one row will not interfere with garments on the other. The height is made suitable for hanging the longest garments thereon without reaching the floor.

It will be noticed that in arranging the hooks on the frame they are placed alternately from one side to the other, as plainly 15 shown in Fig. 2 of the drawings, so when folded the hooks will not lock or interfere with each other. By supporting the hook-carrying frame at the centers of the transverse ends and having the extended ends beyond 20 said supports I obtain a hook-carrying frame free from obstructions around its circumference, allowing the hanging of garments without interference of the supports and increasing the capacity of the rack.

25 Having fully described my invention, what I claim is—

1. A hat and coat rack consisting of a hook-supporting frame, supports at opposite sides thereof, extended ends partially surrounding 30 said supports, and a connecting-bar between the supports, substantially as described.

2. A hat and coat rack consisting of a rectangular hook-supporting frame having inside and outside hook-supporting surfaces, 35 supports at opposite sides thereof, extended ends partially surrounding said supports, and a connecting-bar between said standards, substantially as described.

3. A hat and coat rack consisting of a divided 40 hook-supporting frame, standards or supports hinged to said frame, a divided connecting-bar hinged at the line of division and to said standards or supports at their ends,

and a fastening device to hold the frame in a horizontal position, substantially as described. 45

4. A hat and coat rack, consisting of a divided hook-supporting frame, extended ends rigidly connected to said frame, supporting-standards hinged to said frame, and a divided 50 connecting-bar hinged at the line of division, and at its ends to the standards, substantially as described.

5. A hat and coat rack consisting of a divided hook-supporting frame, having extended ends, supporting-standards hinged to 55 said frame, a divided connecting-bar hinged at the line of division and at its ends to said supports or standards, and a fastening device for holding the hook-frame in a horizontal 60 position, substantially as described.

6. A hat and coat rack consisting of a divided hook-supporting frame, with extended ends, said divided frame being hinged at the line of division, supporting-standards hinged 65 to said frame, a divided connecting-bar hinged at the line of division and at its ends to the standards, and fastening devices for holding the hook-frame in a horizontal position, substantially as described. 70

7. A hat and coat hook, consisting of a divided hook-supporting frame at its top hinged at the line of division, standards hinged thereto, said frame adapted to fold downward, a divided connecting-bar hinged to the lower 75 ends of said standards and at the line of division thereof, adapted to fold upward, and securing devices to hold the hook-frame in a horizontal position, substantially as described. 80

In testimony whereof I affix my signature in presence of two witnesses.

CHARLES A. GERSTBACHER.
